UNITED STATES PATENT OFFICE.

LEONARD B. HARRIS, OF WATERTOWN, NEW YORK.

PUMPING MECHANISM FOR OIL-ENGINES.

1,119,153.

Specification of Letters Patent.

Patented Dec. 1, 1914.

Original application filed October 16, 1912, Serial No. 726,045. Divided and this application filed May 19, 1913. Serial No. 768,484.

To all whom it may concern:

Be it known that I, LEONARD B. HARRIS, a subject of the King of Great Britain, residing at Watertown, in the county of 5 Jefferson and State of New York, have invented new and useful Improvements in Pumping Mechanism for Oil-Engines, of which the following is a specification.

My present invention relates to certain 10 new and useful improvements in oil pumping mechanism especially designed for feeding fuel-oil to internal combustion engines of the Diesel type, the subject matter of the present invention being a division of my 15 pending application Serial No. 726,045, filed October 16, 1912.

One purpose of the invention is to provide simple manually operable and also governor-actuated means for varying at will, 20 and also varying automatically through connections with the engine governor, the quantity of fuel oil fed to the engine cylinders.

Another purpose of the invention is to 25 provide simple means for manually operating the pump-plungers to initially fill the piping system leading to the engine cylinders.

Another purpose of the invention is to 30 provide a simple and compact plural arrangement of pumps adapted to be alternately and successively operated through connections with the engine shaft to pump fuel oil successively to the several engine 35 cylinders.

The invention has in view other more or less important features all of which will be specifically described in the accompanying specification.

40 In order to enable others skilled in the art to understand, make and use my said invention, I will now proceed to describe the same in detail, reference being had for this purpose to the accompanying drawings, 45 wherein:

Figure 1 is a front elevation of one form of pumping mechanism constructed according to the present invention. Fig. 2 is a side elevation showing the oil supply to the 50 engine-cylinder and showing also the connection between the engine governor and pumping mechanism. Fig. 3 is an enlarged detail view, partly in section, of the pump cylinders and their plungers. Fig. 4 is an end view of the same. Fig. 5 is a modified 55 arrangement of means for adjusting the plunger operating mechanism. Fig. 6 is a vertical section through one of the engine cylinders and showing the driving connection between the engine shaft and the pumping mechanism. Fig. 7 is a detail longitudinal section of the control lever shaft showing the lost-motion connection with its levers. Fig. 8 is a section on the line 8-8 of Fig. 7. Fig. 9 is a detail perspective 65 view of the bushing carried by the control lever.

In the accompanying drawings and the following description I have elected to illustrate and describe my improved pumping mechanism as associated with a two-cylinder engine, but obviously the same may be embodied in an engine having more or less cylinders without departing from the spirit of the invention, the present showing 75 being merely by way of example.

Referring to the accompanying drawings wherein like reference numerals indicate the same parts throughout the several views, the numeral 1, designates the base member 80 or casting of the engine, which as above indicated may be suitably designed for any desired number of cylinders depending upon the horse-power to be developed, and upon this base member the engine cylinders 85 2, are mounted. As more clearly illustrated in Fig. 6 the engine cylinders as here shown are of stepped form, that is to say each cylinder has alined bores of different diameter, the smaller bore 3 being the power or working cylinder of the engine, and the larger bore 4 being the scavenging cylinder and compressed air motor starting cylinder combined. Within these two cylinders is fitted a stepped piston having heads 5 and 6 corresponding in diameter to the bores 3 and 4 respectively, the head 5 being the working or power cylinder and the head 6 being the combined starting and scavenging piston. The connecting rod 7 is connected by a 100 crank 8 to the engine shaft 9 in the usual way. The fuel oil is fed into the top of each cylinder through an atomizer 55 controlled by an atomizer valve 56, carried by a stem 57, the valve being lifted at proper intervals by means of levers 58, the said atomi-

90

95

100

105

izer valve 56 being normally held to its seat by means of a coiled spring 58^a acting upon the levers 58.

In the present instance the pumping mechanism is shown as mounted upon one end of the base member, but obviously the same may be otherwise mounted.

The fuel-oil, as stated, is fed to an atomizer located in the head of each engine cylinder, a separate plunger-pump being employed to deliver oil to each atomizer. In the present instance I have shown a pair of pumps, the plungers of which are actuated alternately by a common operating element, it being always understood of course, that the number of pumps employed is dependent upon the number of cylinders going to make up the engine. In the instance shown, and as more clearly illustrated in Figs. 1 and 3, each pump, there being two shown, comprises a vertically arranged cylinder 61 in which is reciprocally mounted a plunger 62, the latter being normally held in retracted position by means of a coiled spring 63 coiled about the lower end of a stem extension 64 of the plunger, said extension passing through a guide 65, Fig. 1, between the end of which guide and a nut 66, carried by the stem extension, the said coiled spring is mounted, the nut 66 serving to adjust the tension of the spring. The pump cylinder 61 is coupled at its upper end with an intake pipe 67 leading from the fuel oil supply tank 68, through pipe 68^a, as more clearly shown in Fig. 2, and the oil is delivered to the atomizer of the engine cylinder or cylinders through the delivery pipe or pipes 69 leading from each pump cylinder 61, suitable check valves 69^a, 69^b, being provided in the pipes 67, and a further check valve 69^c being arranged in each pipe 69 to effect proper operation of the pumps, all as more clearly shown in Figs. 1 and 3. For convenience the intake pipe 67 is connected at its opposite ends respectively to the two pump cylinders as shown, and the oil feed pipe 68^b leading from the oil tank 68 is connected to the pipe 67 by means of a T-coupling 70. The stem of each of the extensions 62 is provided intermediate its ends with a yoke 71 as more clearly shown in Figs. 1 and 4, through which yoke passes one arm 72 of a bell crank lever 73, the longer arm 74 of the bell crank lever being arranged to be acted upon by a rotary cam 75 mounted upon a shaft 76 driven from a shaft 77, the latter being driven from the main shaft 9 of the engine, as shown in dotted lines, Fig. 2, and in full lines in Fig. 6.

As before indicated I have, in the present instance, shown two pumps, and I have provided a separate and distinct actuator for operating the plunger of each pump, the said actuators being duplicates of one an-

other, and so arranged that the cam 75 will alternately engage the actuators to alternately and successively actuate the pump plungers 62. As will be seen by referring to Fig. 1 the two bell crank actuators 73 are arranged opposite each other, the arms 74 being located in parallelism, and on opposite sides of the cam shaft 76 so as to be alternately engaged by the cam 75 carried by said shaft. It will be perfectly apparent that the amount of oil delivered to each of the engine cylinders will depend upon the length of stroke of the oil feed pump plungers 62, and I have provided novel means for varying the length of stroke of these plungers. I have also provided a lost motion connection between the pumping means and the manual control lever of the engine whereby the oil feed pumps may be set in motion when the manual control lever is moved to a certain position, but which oil feed pumps will remain idle until the manual control lever has been moved to the proper position, the initial movement of the control lever having no effect on the operation of the oil feed pumps, this initial movement of the control lever serving merely to admit compressed air to the combined scavenging and compressed air starting motors, as clearly set forth in my co-pending application hereinbefore referred to.

Each of the bell crank levers 73 is mounted to swing on a fulcrum pin 78 carried by a laterally shiftable slide plate 79, the said slide plates, of which there are two, one for each bell crank lever, being free to slide in dove-tailed guides 80. The movement of these slides with their fulcrum pins and bell crank levers is effected through the medium of two worm spindles 81 and 82, each spindle carrying a pair of right and left hand worms 83 and 84, respectively, each of which pair of worms is in mesh or gear with a worm sector 85, the sectors revolving on the pins which carry the bell crank levers 73, so that whatever movement is imparted to the sectors will likewise be imparted to the laterally shiftable slide plates 79 which carry the bell crank levers, so as to move the latter to bring their arms 74 toward and from each other or toward and from the cam 75 on the shaft 76. The worm sectors 85 are arranged to revolve on their fulcrum pins 78 and roll as pinions on a rack depending upon which of the worm spindles 81 or 82 is stationary, the stationary worm forming the rack, thereby causing the fulcrum pins 78 with their bell crank levers 73 to move away from each other or closer together according to the direction of revolution of the worm spindles 81 or 82, in order to increase or diminish the stroke of the fuel pump plungers 62. The shorter arm 72 of each bell crank lever has a sliding connection with an oscillating

tumbler block 86 carried by each of the yokes 71 of the pump plungers, the said shorter arms 72 sliding back and forth through their tumbler blocks as lateral adjustments of the slides 79 take place or are made. The worm spindle 81 may be rotated to effect proper movement of the bell crank lever 73 and the slide plate 79 by which it is carried by means of a connection with the engine governor 87, as more clearly shown in Fig. 2, this being accomplished by providing the spindle 81 with a pinion 88 that is in mesh with a rack 89, Fig. 1, carried by a vertically moving rod 90 connected at its upper end to a lever 91 having a suitable connection with the governor 87 so as to move up or down depending upon the speed of the engine, and through the rack and pinion connection with the worm spindle 81 and its worms and worm sectors 83, 85, move the bell crank levers automatically toward and from each other to automatically control the delivery of fuel oil to the engine cylinders or their atomizers, the lever 91 being normally pulled in a downward direction by means of the coiled spring 91. I also provide an operative connection between the manual control lever 41 of the engine, and the said bell crank levers 73, so as to move said levers closer together or farther apart depending upon the position of said control lever, so that the greater the movement given to this lever the nearer together the arms 74 of the bell crank levers will be brought and the greater the supply of oil pumped to the engine cylinders. This connection between the manual control lever and the bell crank levers consists of a crank arm 93 carried by the end of the shaft 42 upon which the control lever 41 is mounted, said crank arm 93 having a link connection 94 with a bell crank lever 95 to the longer arm of which is pivoted a rack 96 that meshes with a pinion 97, Fig. 1, fixed on one end of the worm spindle 82, the connections referred to being shown in dotted lines in Fig. 2. The lever 93 is preferably arranged on a dead center so that whichever way the control lever 41 is moved, that is to say to either "ahead" or "astern" position, the rack 96 will always move in the same direction. By reason of this construction it will be seen that whenever the manual control lever 41 is moved to bring its locking dog into engagement with the second notch in the dial plate 46 with which the control lever operates, the worm spindle 82 through its rack and pinion connections 96 and 97, bell crank 95 and link and crank connections 94 and 93, with the shaft 42 of the control lever, will bring the arms 74 of the bell crank levers close together so as to be engaged and operated by the cam 75 on the shaft 76, the distance between the arms 74 and the bell crank lever 73 varying, depending upon the amount of movement given the control lever 41, it being understood, of course, that the dial 46 about which the control lever moves, has several fuel feeding positions to any one of which the control lever may be moved and locked and each position representing a different supply of oil, as for instance "initial fuel feed," "half fuel feed," and "full fuel feed," these positions being duplicated on opposite sides of the dial so that the control lever may be set to proper position for running the engine "ahead" or "astern."

The crank 93 is provided with a bushing 98, as more clearly shown in Figs. 7, 8, and 9, at the point where it is mounted upon the control lever shaft 42, said bushing having a substantially semi-circular cut out portion partially surrounding the said shaft and terminating at its ends in two shoulders or abutments 99, with either one or the other of which a key 100 engages, said key being carried by the shaft 42, so that during the initial movement of the control lever in either direction, that is to say to the right or to the left, no movement will be imparted to the crank arm 93, and its associated mechanism leading to the fuel feed pumps. By this means I am able to move the control lever to the first notch position on the dial 46 in order to initially start the engine by compressed air power and without feeding fuel oil to the engine cylinders or opening the atomizer. Immediately, however, the control lever is moved past the first notch position on the dial the key 100 will engage one or the other of the shoulders 99, depending upon the direction of movement of the control lever, the crank arm 93 will then begin to turn with the control lever shaft 42 to move the bell crank levers 73 in position for engagement with their actuating cam 75, it being understood that when in normal position, or in the idle position of the parts, the levers will be so widely separated that the cam 75 cannot engage the arms 74 and there will, therefore, be no actuation of the pump plungers.

If it is desired to alter the position of the bell crank levers 73 without changing the position of the manual control lever, this may be effected by means of a manually operable controller shown in the present instance as consisting of a hand wheel 101 mounted upon the end of the worm spindle 82, as more clearly shown in Figs. 1 and 2. This hand wheel 101 may be adjusted at the will of the operator to vary the fuel oil feed to the engine cylinders or their atomizers, without altering the position of the manual control lever. In effecting this adjustment the rack 96 is first lifted out of engagement with the pinion 97, the hand wheel 101 being then turned to effect proper adjustment.

ment of the bell crank levers 73, relative to the actuating cam 75 and the rack then again allowed to drop into engagement with its pinion 97. A spring 96^a normally acts 5 upon the rack 96 to hold the same in mesh with its pinion. This means for adjusting the position of the bell crank levers independently of the manual control lever, will be found to be of advantage also in case of 10 leakage of oil in the pump packing or glands, or in the event of a heavier grade of oil being used, such as will require a greater stroke of the oil feed plungers.

In addition to the engine driven cam 75 15 for operating the oil feed pumps, I have provided a manually operable cam for operating the pumps through the arms 74 of the bell crank levers 73, this manually operable cam being employed primarily to fill up the 20 oil piping system leading from the fuel feed pumps to the atomizers, before starting the engine, in case these pipes should have become empty or through loss of pressure caused by leakage while the engine has been 25 standing idle for any considerable time. This hand operated means referred to consists of a cam 102 mounted upon a shaft 103 located below the shaft 76 and which shaft 103 carries a crank arm 104 upon the lower 30 end of which is mounted a handle 105, all as more clearly shown in Figs. 1 and 2. As will be apparent, rotation of the shaft 103 will cause its cam 102 to alternately engage the arms 74 of the bell crank lever 73 in 35 order to actuate the pump plungers, and thus feed fuel oil through the system of pipes leading to the engine cylinders or their atomizers 56.

The charges of fuel oil are admitted to 40 the working cylinders of the engine through an atomizer 56, Fig. 6, the fuel oil being sprayed or atomized under pressure upon the lifting of the valve 57, said valves being lifted at regular intervals through the 45 medium of the levers 58, there being two such levers associated with the stem of the valve 57 when the engine is of the reversible or marine type, but only one such lever when the engine is of the straightaway or station- 50 ary type. One of the levers 58 of the two referred to is employed to lift its valve when the control lever is set for running the engine "ahead" and the other of said levers is employed when the control lever 55 is set for running the engine "astern". The operating mechanism for these levers is so arranged that one or the other will be automatically set in position for operation by the movement of the manual control 60 lever, but as this mechanism forms no part of the present invention, the same forming the subject matter of a separate application, Serial Number 769,926, filed May 26, 1913, it need not be described in detail herein.

65 In Fig. 5 I have shown a slightly modi-

fied form of adjusting means for the bell crank levers that control the operation of the pump plunger. Instead of employing the sectors 85 I employ internally threaded sleeves 85^a having threaded engagement with oppositely threaded portions 84^a mounted upon the shafts 81^a and 83^a 82^a, the said sleeves 85^a that coöperate respectively with the threaded portions 83^a 84^a, being interconnected by arms 86^a and the bell crank levers 74^a for actuating the pump plungers being carried by said arms 86^a.

70 From the foregoing description taken in connection with the accompanying drawings, it will be seen that I have provided a simple arrangement of fuel oil pumping mechanism with controlling means associated therewith, whereby the quantity of fuel oil fed to the engine cylinders or their atomizers may be controlled manually from the control lever or manually by an auxiliary control device, either of these devices being 80 optionally manipulable, and I have also provided an automatic control mechanism having a connection with the engine governor 85 for automatically varying the quantity of oil fed to the engine cylinders or their atomizers 90 during the running of the engine.

95 While I have herein shown and described a preferred embodiment of my invention, I do not wish to be understood as limiting myself to the precise details shown and described except as I may be limited by the appended claims.

100 What I claim is:—

1. In an internal combustion engine, pumping mechanism for feeding fuel oil to the cylinders of the engine, comprising a pair of pump cylinders, and coöperating plungers, a laterally adjustable actuator for each of said plungers, means for successively operating said plunger actuators, and means for adjusting the actuators toward and from their operating means and relative to said plungers for adjusting the stroke of the 110 latter.

105 2. In an internal combustion engine, pumping mechanism for feeding fuel oil to the engine cylinders comprising plunger pumps, a laterally adjustable actuator for each of the pump plungers, means for successively operating said plunger actuators, and manually operable means for moving the said plunger actuators laterally into and out of coöperative relation with the operating means and relative to said plungers for adjusting the stroke of the latter.

115 3. In an internal combustion engine, pumping mechanism for feeding fuel-oil to the engine cylinders, embodying pump cylinders and coöperating plungers arranged in spaced parallel relation, an oscillating actuator for each plunger, each actuator having a part in slidable engagement with its plunger and said actuators being arranged be- 120 125

tween the pump plungers, means for simultaneously adjusting the actuators toward and from each other to vary the stroke of the plungers, and means for alternately operating the actuators.

4. In an internal combustion engine, pumping mechanism for feeding fuel oil to the engine cylinders, comprising plunger pumps, a laterally adjustable actuator 10 operatively associated with each of the pump plungers and having a part in sliding engagement therewith, power operated means for successively operating said plunger actuators by engaging another part thereof, and 15 an independent manually operable means for operating said actuators.

5. In an internal combustion engine, pumping mechanism for feeding fuel oil to the engine cylinders, comprising plunger 20 pumps, a laterally adjustable actuator for each of the pump plungers, slides in which said actuators are pivotally mounted, power operated means for successively operating said plunger actuators, and a manually operable controller for governing the operation 25 of the plunger actuators.

6. In an internal combustion engine, pumping mechanism for feeding fuel oil to the engine cylinders, comprising plunger 30 pumps, an actuator for each of the pump plungers, said actuators being arranged in pairs, opposed slides in which the said actuators are pivotally mounted, and a common operating element interposed between the 35 pair of actuators.

7. In an internal combustion engine, pumping mechanism for feeding fuel oil to the engine cylinders, comprising plunger pumps, an actuator for each of the pump 40 plungers, said actuators being arranged in opposed pairs, a laterally adjustable slide in which each actuator is pivotally mounted, and a single cam interposed between each 45 pair of actuators for alternately operating the actuators.

8. In an internal combustion engine, pumping mechanism for feeding fuel oil to the engine cylinders comprising plunger pumps, a laterally adjustable actuator for each of 50 the pump plungers, said actuators being arranged in pairs, a power driven cam interposed between each pair of actuators, and an independent manually operable cam interposed between actuators.

9. In an internal combustion engine, pumping mechanism for feeding fuel oil to the engine cylinders, comprising plunger pumps, a pair of freely movable slides adjustable toward and from each other, a bell 55 crank lever pivotally mounted on each slide for operating the pump plungers, means for adjusting the slides laterally, and cam means for alternately operating said bell crank levers.

10. In an internal combustion engine,

pumping mechanism for feeding fuel oil to the engine cylinders, comprising plunger pumps, a bell crank lever for operating each plunger, said bell crank levers being arranged in pairs, and a cam disposed between the arms of each pair of bell crank levers for alternately operating the latter.

11. In an internal combustion engine, pumping mechanism for feeding fuel oil to the engine cylinders, comprising plunger 75 pumps, a bell crank lever for operating each pump plunger, said bell crank levers being arranged in pairs, a power driven cam disposed between the arms of each pair of bell crank levers for alternately operating 80 the levers, and a second manually operable cam also disposed between each pair of bell crank levers for operating the latter independently of the power driven cam.

12. In an internal combustion engine, 85 pumping mechanism for feeding fuel oil to the engine cylinders, comprising plunger pumps, a bell crank lever for each pump plunger, means for successively operating said bell crank levers, and means for adjusting the bell crank levers toward and from each other and said operating means to vary the stroke of the plungers.

13. In an internal combustion engine, 95 pumping mechanism for feeding oil to the engine cylinders, comprising plunger pumps, a bell crank lever for each of the pump plungers, means for successively operating said bell crank levers, and manually operable means for adjusting the bell crank 100 levers toward and from each other and toward and from their operating means to vary the stroke of the plungers.

14. In an internal combustion engine, 105 pumping mechanism for feeding fuel oil to the engine cylinders, comprising plunger pumps, bell crank levers for operating said plungers, laterally adjustable slides in which said bell crank levers are pivotally mounted, an engine governor, a connection between 110 said governor and bell crank levers for automatically shifting the position of the latter to vary the stroke of the plungers, and means for alternately operating said bell crank levers.

15. In an internal combustion engine, 115 pumping mechanism for feeding fuel oil to the engine cylinders, comprising plunger pumps, bell crank levers for operating said plungers, an engine governor, a connection between 120 said governor and bell crank levers for automatically varying the position of the lever to vary the stroke of the plungers, and independent manually operable means for adjusting the position of the bell crank 125 levers toward and from the operating means.

16. In an internal combustion engine, pumping mechanism for feeding fuel oil to the engine cylinders, comprising plunger pumps, bell crank levers having operative 130

- connections with said plungers, said bell crank levers being arranged in pairs, means for alternately operating said levers, means for adjusting each pair of bell crank levers toward and from each other, a manually operable controller, and a connection between said controller and adjusting means. 17. In an internal combustion engine, pumping mechanism for feeding fuel oil to the engine cylinders, comprising plunger pumps, bell crank levers having operative connections respectively with said plungers, said bell crank levers being arranged in pairs, means for alternately oscillating the levers, means for adjusting each pair of bell crank levers toward and from each other, a manually operable controller, and a lost motion connection between said controller and adjusting means. 18. In an internal combustion engine, pumping mechanism for feeding fuel oil to the engine cylinders, comprising plunger pumps, a bell crank lever for operating each plunger, a power driven cam for operating the bell crank levers, a worm spindle for adjusting the bell crank levers toward and from the power driven cam, and means for operating said worm spindle. 19. In an internal combustion engine, pumping mechanism for feeding fuel oil to the engine cylinders, comprising plunger pumps, a bell crank lever for operating each plunger, a power driven cam for operating the bell crank levers, a worm spindle for adjusting the bell crank levers toward and from the power driven cam, a controller, and a connection between the controller and the worm spindle for rotating the latter. 20. In an internal combustion engine, pumping mechanism for feeding fuel oil to the engine cylinders, comprising plunger pumps, a bell crank lever for operating each plunger, a power driven cam for operating the bell crank levers, a worm spindle for adjusting the bell crank levers toward and from the power driven cam, a controller, a connection between the controller and the worm spindle for rotating the latter, and means independent of said controller for rotating the worm spindle. 21. In an internal combustion engine, pumping mechanism for feeding fuel oil to the engine cylinders, comprising plunger pumps, bell crank levers having operative connections respectively with said plungers, said bell crank levers being arranged in pairs, a power driven cam arranged between each pair of bell crank levers for alternately operating the latter, a pair of worm spindles associated with each bell crank lever for adjusting the latter toward and from their operating cam, a controller, and a connection between said controller and one of said worm spindles. 22. In an internal combustion engine, pumping mechanism for feeding fuel oil to the engine cylinders, comprising plunger pumps, bell crank levers having operative connections respectively with said plungers, said bell crank levers being arranged in pairs, a power driven cam arranged between each pair of bell crank levers for alternately operating the latter, a pair of worm spindles associated with each bell crank lever for adjusting the latter toward and from their operating cam, a controller, and a connection between said controller and one of said worm spindles. 23. In an internal combustion engine, pumping mechanism for feeding fuel-oil to an engine cylinder, embodying a pump cylinder and coöperating plunger having a yoke, an oscillating tumbler-block carried by said yoke, a laterally adjustable bell-crank lever for actuating the plunger, said lever having one arm in slidable engagement with the said tumbler-block, and means for engaging and actuating the other arm of the bell-crank lever to reciprocate the plunger. 24. In an internal combustion engine, pumping mechanism for feeding fuel-oil to an engine cylinder, embodying a pump cylinder and coöperating plunger, an oscillating tumbler-block carried by the plunger, a pivotally mounted bell-crank lever having one arm in sliding engagement with said tumbler-block, an actuating member positioned to engage and actuate the other arm of the bell-crank lever, and means for adjusting the position of the bell-crank lever relative to its plunger and actuating member to vary the length of stroke of the plunger. 25. In an internal combustion engine, pumping mechanism for feeding fuel oil to the engine cylinders, comprising plunger pumps, bell crank levers having operative connections respectively with the pump plungers, a laterally adjustable slide in which each lever is mounted for oscillation, a worm-sector journaled in each slide, worms in mesh with said sectors, and means for rotating the worms to adjust the slides laterally. 26. In an internal combustion engine, pumping mechanism for feeding fuel oil to the engine cylinders, embodying pump plungers, bell crank levers having operative connections respectively with said plungers, means for operating the bell-crank levers, laterally adjustable slides in which the bell crank levers are mounted for oscillation, opposed worm-sectors journaled in each slide, worm-shafts having worms thereon in mesh with the sectors, and means for rotating the said worm shafts to adjust the slides laterally and move the bell-crank levers toward and from their operating means. 27. In an internal combustion engine, pumping mechanism for feeding fuel oil to

an engine cylinder, embodying a pump plunger, a bell-crank lever one arm of which has an operative connection with said plunger, a rotary cam arranged to act upon the other arm of the bell-crank lever to impart oscillations thereto, a laterally adjustable slide in which the bell crank lever is journaled for oscillation, a worm-sector journaled in the slide, a worm-shaft in mesh with the sector, and means for rotating the worm-shaft in opposite directions to adjust the slide and its bell-crank lever toward and from the said cam.

28. In an internal combustion engine, pumping mechanism for feeding fuel oil to the engine cylinders, embodying pump plungers, bell crank levers each having one arm slidably engaging a pump-plunger, means coöperatively associated with the other arm of the bell-crank levers for imparting oscillations thereto, a laterally adjustable slide in which each bell-crank lever is journaled for oscillation, a pair of opposed worm-sectors journaled in each slide, a pair of worm-shafts each having worms in mesh with the said sectors, and independent means for rotating the said shafts.

29. In an internal combustion engine, pumping mechanism for feeding fuel oil to the cylinders of the engine, comprising a pair of pump cylinders each having a co-

operating plunger, a laterally adjustable oscillating actuator for each plunger, each actuator having arms arranged at substantially right angles to each other, and one of which arms has sliding engagement with its associated plunger, operating means for engaging the other arm of each actuator, and means for adjusting the actuators toward and from their operating means to vary the length of stroke of the plungers.

30. In an internal combustion engine, pumping mechanism for feeding fuel oil to the engine cylinder, comprising a pump cylinder having a coöperating plunger, a laterally adjustable oscillating actuator for operating said plunger, said actuator having arms arranged at substantially right angles to each other, and one of which arms has a sliding connection with the plunger, operating means for engaging the other arm of the actuator, and means for adjusting the actuator toward and from its operating means to vary the length of stroke of the plunger.

In testimony whereof I have hereunto set my hand in presence of two subscribing witnesses.

LEONARD B. HARRIS.
